UNITED STATES PATENT OFFICE.

BOYD M. JOHNSON, OF METUCHEN, NEW JERSEY, ASSIGNOR TO THE CARBORUNDUM COMPANY, OF NIAGARA FALLS, NEW YORK, A CORPORATION OF PENNSYLVANIA.

KILN.

Application filed September 21, 1925. Serial No. 57,591.

The present invention relates broadly to kilns, and more particularly to kilns of the so-called chamber or compartment type.

Developments in the art to which the present invention relates show the necessity of constructing kilns with the object in view of reducing both the operating time and cost while maintaining uniform conditions as to temperature throughout the chamber or chambers being fired.

The present invention has for certain of its objects the provision of a chamber kiln in which each chamber is provided with improved heating means so constructed as to effect uniform heating, the different chambers being so interconnected as to permit heat recovery from both a chamber which has just been fired and from the contents of such chamber, and to permit a fresh charge in another chamber to be preliminarily preheated.

In the accompanying drawings there is shown for purposes of illustration only a preferred embodiment of the present invention, it being understood that the drawings do not define the limits of my invention, as changes in the construction and operation disclosed therein may be made without departing either from the spirit of the invention or the scope of my broader claims.

In the drawings:—

Figure 1 is a longitudinal sectional view through one form of kiln embodying the present invention.

Figure 2 is a top plan view of the construction illustrated in Figure 1.

Figure 3 is a vertical transverse sectional view, on an enlarged scale, along the line 3—3 of Figure 2 looking in the direction of the arrows.

It will be understood in considering the present invention that the utility is not limited to any particular number of chambers comprising the entire kiln, the drawings however having for their object the purpose of illustrating the smallest number of chambers which can conveniently be used in carrying out the present invention, it being apparent to those skilled in the art that any desired number of additional chambers may be added to the kiln to give the capacity desired.

Heretofore in the art to which the present invention relates there has been considerable difficulty experienced in obtaining an effec-

tive distribution of preheated air from one chamber into another for the reason that it is possible to preheat air to such an extent as to make it impractical to collect such preheated air by means of a fan and then blow the same into the combustion chamber as has heretofore been contemplated. The present invention, therefore, has for one of its objects the construction of a kiln in such manner that air preheated to any desired temperature may be conveniently passed from one chamber or compartment to another in such manner as to obviate the use of any fan or equivalent means for handling such preheated air, and under such conditions as to insure effective distribution of the preheated air and with a resultant desirable flame condition, it being understood that a fan or fans for producing the necessary draft but not for handling the preheated air may be provided.

In carrying out the present invention there may be any desired number of chambers A, B, C, D and E herein illustrated as being five in number. Each of these chambers may be of any desired dimension and generally construction embodying side walls 2 connected by roofs 3 preferably of arched construction as customary in the art. The floor 4 of the kiln, however, is of special construction embodying a plurality of spaced longitudinally extending flues 5, each flue being preferably comparatively narrow. Throughout the main body of each chamber these flues 5 are covered by a protective covering 6 partially enclosing the flues. The covering 6 cooperates in each chamber at one side with a baffle wall 7, and at the other side is cut away to provide a series of ports 8 communicating with the flues 5.

The space between a baffle wall 7 and its adjacent division wall 2 forms a flue space which carries the gases to the top of the furnace. Within each of these flue spaces is a radiating combustion chamber 10 preferably extending throughout substantially one entire dimension of the chamber and comprising a lower flue 11 and an upper flue 12 separated by a partition 13 terminating short of one end of the flues 11 and 12. The lower wall of the flue 11 is constructed to provide a plurality of ports 14 communicating with the flues 5, while the upper wall of each of the flues 12 is constructed to pro-

vide a plurality of similar ports 15, these ports being preferably substantially uniformly spaced throughout one entire dimension of the chamber.

5 The flues 5 communicate at one end with a transversely extending passage 16 and at the other end with a similar passage 17, these two passages in turn communicating at one side of the kiln with a longitudinally 10 extending passage 18, these passages providing means whereby a circulation of heated air may be obtained as desired, and as pointed out more fully hereinafter.

Extending longitudinally of the kiln is a 15 flue 19 communicating at one end with a stack (not shown), and communicating at spaced points throughout its length with transversely extending flues *a*, *b*, *c* and *d*. The flue *a* is in communication with the 20 chamber A through any desired number of ports 20 adapted to be controlled by a damper or dampers 21, and is also in communication with the chamber B by any desired 25 number of ports 22 adapted to be controlled by a damper 23. The flue *b* is likewise in communication with the chamber C through damper controlled ports 24; the flue *c* is in communication with the chamber D through damper controlled ports 25 and the flue *d* 30 is in communication with the chamber E through damper controlled ports 26.

Extending into each of the burner flues 11 of the radiating combustion chamber is a burner 27 for delivering any desired type of 35 fuel thereto, each of the burners being adapted to be individually controlled at will.

In the operation of the kiln, it may be assumed that the chamber A contains a charge 40 of ware or other desired material positioned therein preparatory to firing. The chamber B is empty, it being assumed that this is the next chamber which will have a charge placed therein. The chamber C is empty, the charge having been removed therefrom 45 subsequently to the removal of the charge from chamber B, and the chamber D is loaded with a charge which has just been burned and which is cooling. Under these conditions chamber E would be charged and under fire.

Assuming a condition as above set forth, 50 air may be admitted to the chamber C through a suitable opening 28. This air will then divide as indicated by the arrows, part 55 of the air passing upwardly over the baffle wall 7 and through ports 29 provided in each chamber between the burner and the baffle wall and thence into the flues 5, while another portion will pass directly through the 60 ports 8 into the flues 5. Inasmuch as the flues extend throughout substantially the entire dimension of the chamber, this air will be in distributed condition in the form of a 65 plurality of streams. In this condition it will travel to the ports 14 in the bottom of

the flue 11 in the radiating combustion chamber of the compartment D. The entering streams will combine and travel below the partition 13 into the upper flue 12 and thence through the ports 15 into the radiating combustion chamber. After leaving these ports, the streams may again divide, part of the air passing downwardly as indicated by the arrows through the ports 29 into the flues 5 and part of the air passing upwardly over the baffle wall 7 and into the flues through the ports 8. That portion of the air passing upwardly over the baffle will come into direct contact with the previously fired ware and will absorb heat therefrom and from the chamber. The air passing through the ports 29 will likewise be pre-heated, and this highly preheated air will pass in distributed condition into the burner passage 11 within the chamber E. Fuel will at the same time be supplied to this passage through the burner 27, and by reason of the distributed air supply effective combustion will take place. The heated products of combustion will then flow into the flue 12 75 and escape into the chamber E for heating the ware therein, part of the combustion products passing below the charge and part of the combustion products passing therethrough as clearly indicated by the arrows. 80

These combustion products will impart their heat to the charge within the chamber E, and will thereupon leave the chamber through the ports 8 and combine with the products in the flues 5, the combined streams then traveling into the transverse passage 16, and the longitudinally extending passage 18 to the passage 17 at the opposite end of the kiln. These products, which still retain a considerable portion of their heat will flow 90 from the passage 17 into the radiating combustion chamber in the chamber A, and from this combustion chamber they will flow through and around the chamber A, as before described in detail, for effectively pre-heating the charge in this chamber. Thereafter the products will enter the chamber B as indicated by the arrows and will pass outwardly therefrom to the flue *a* and thence to the stack through the flue 19. 95

It will be understood that the respective dampers in the flues *a*, *b*, *c* and *d* are all positioned so as to permit a circulation as set forth, and that the flues 5 are divided at intermediate points by suitable dampers 100 120 30. After the charge in the chamber E has been brought to the desired temperature, the dampers will be arranged to supply air directly to the chamber D which will be pre-heated by the ware in chamber E and delivered in preheated condition to the radiating combustion chamber for the chamber A. This operation will be repeated each time a compartment is emptied, whereby at 105 least one of the chambers may always be 110 125 130

under fire and the heat from a previously fired chamber or chambers may be utilized for improving the combustion conditions.

- 6 Certain of the advantages of the present invention arise from the provision of a kiln structure having a radiating combustion chamber for each chamber of the kiln, whereby effective heating of the chambers is obtained.
- 10 Further advantages arise from the provision of a construction of such nature that highly preheated air may be effectively passed from one chamber to another without the necessity of employing mechanical
- 15 circulating means such as a fan for handling the preheated air, and under such conditions that effective distribution is insured.

I claim:

1. In a kiln, a plurality of chambers, a radiating combustion means in each chamber, and means for conducting air in distributed condition from a previously fired chamber into the combustion means of a chamber under fire in distributed condition.
- 25 2. In a kiln, a plurality of chambers, and radiating combustion means for conducting air from a previously fired chamber into a chamber under fire in distributed and highly preheated condition.
- 30 3. In a kiln, a plurality of chambers, a transversely extending radiating combustion means in each chamber, and spaced longitudinally extending flues for conducting air from a previously fired chamber into the radiating combustion means of a chamber under fire in distributed condition, said radiating combustion means having ports therein opening into said longitudinally extending flues.
- 35 4. In a kiln, a plurality of chambers, radiating combustion means for each of said chambers, and means for delivering highly preheated air from a previously fired chamber into the combustion means of a chamber under fire in distributed condition.
- 45 5. In a kiln, a plurality of chambers, a

floor having a plurality of relatively narrow flues extending throughout substantially one entire dimension of each of the chambers, and a radiating combustion means in each 50 of said chambers communicating directly with said flues.

6. In a kiln, a plurality of chambers, a floor having a plurality of relatively narrow flues extending throughout substantially one 55 entire dimension of each of the chambers, and a radiating combustion means in each of said chambers transverse to and communicating with said flues through a plurality of spaced ports.

7. In a kiln, a chamber for the reception of material to be fired, combustion means for said chamber of the radiating combustion passage type, said combustion means having a plurality of spaced ports for the distribution of products of combustion to said chamber and a plurality of spaced ports for the introduction of preheated air to support combustion therein, and a plurality of flues for delivering preheated air to said last 70 mentioned ports.

8. In a kiln, a plurality of chambers, radiating combustion means in each of said chambers, and a plurality of relatively narrow flues interconnecting said chambers and 75 combustion means.

9. In a kiln, a plurality of chambers, radiating combustion means in each of said chambers, a plurality of relatively narrow flues interconnecting said chambers and combustion means, and a damper controlled off-take for each of said chambers.

10. A chamber kiln having a radiating combustion means therein, which is substantially coextensive with one dimension of 85 the chamber, and which has outlet ports distributed therealong whereby a widely and substantially uniform distribution of heat is secured through the chamber.

In testimony whereof I have hereunto set 90 my hand.

BOYD M. JOHNSON.
